his Atty's -

HENRY C. FRY, OF PITTSBURG, PENNSYLVANIA, ASSIGNOR TO
HIMSELF, FRANK SEMPLE, AND JOHN D. REYNOLDS.

Design No. 3,221, dated November 3, 1868.

DESIGN FOR THE ORNAMENTATION OF GLASS-WARE.

The Schedule referred to in these Letters Patent and making part of the same.

To all whom it may concern:

Be it known that I, HENRY C. FRY, of the city of Pittsburgh, in the county of Allegheny, and State of Pennsylvania, have invented a new, and useful, and original Design for Glass-Ware; and I do hereby declare the following to be a full, clear, and exact description thereof, reference being had to the accompanying drawing, making a part of this specification, in which—

Figure 1 is a plan view of my improved design for glassware, repeated around a central point, the part included within the lines $x-x$ and $y-y$ representing the design.

My improved design or configuration for glassware consists of a fluting, a , oval at one end, as at b , and angular or sharp-pointed at the other, as at c , and with gradually-converging sides, d .

By lines or grooves crossing each other, diamond-shaped or rhomboidal figures, s , are formed adjacent to the angular end, c , and extending from it inward,

toward any fixed central point, around which the design may be repeated.

The rhomboids s decrease in size as they recede from the angular end, c .

Such a design or configuration may be repeated on the lower part of the bowl of a goblet, or around the knob or handle, or central point, of the oval of a dish or dish-cover, or around any central point arbitrarily chosen.

What I claim as my invention, and desire to secure by Letters Patent, is—

The design for glass-ware, herein set forth and shown.

In testimony whereof, I, the said HENRY C. FRY, have hereunto set my hand.

HENRY C. FRY.
